E. T. SEIFERT.
LADY'S UNDERGARMENT.
APPLICATION FILED MAR. 16, 1916.

Patented Jan. 30, 1917.

Ernest T. Seifert, Inventor.
By his Attorney
Phillips Abbott.

UNITED STATES PATENT OFFICE.

ERNST T. SEIFERT, OF RICHMOND HILL, NEW YORK, ASSIGNOR TO JULIUS KAYSER & CO., OF NEW YORK, N. Y., A CORPORATION OF NEW YORK.

LADY'S UNDERGARMENT.

1,214,084.

Specification of Letters Patent. Patented Jan. 30, 1917.

Application filed March 16, 1916. Serial No. 84,501.

To all whom it may concern:

Be it known that I, ERNST T. SEIFERT, a citizen of the United States, and a resident of Richmond Hill, county of Queens, and 5 State of New York, have invented a new and useful Improvement in Ladies' Undergarments, of which the following is a specification.

My invention is adapted to a variety of 10 ladies' undergarments, for example, an undervest, chemise, union suit, corset cover, camisole and the like.

The special features of the invention are 15 that instead of making and applying to such garment the usual shoulder straps provided with an interiorly located draw string to adjust the garment about the bust and shoulders of the wearer, I do away entirely with all the material of the garment above the 20 bust line or neck opening, and so fashion it and so embody a draw string, or equivalent, therewith, that the draw string shall not only perform its usual functions, but shall also alone constitute the shoulder straps of 25 the garment which are ordinarily desired for day use, and when it is desired to use the garment for evening wear, all that will be necessary is to pass the portion of the draw string forming the shoulder straps be- 30neath the arms instead of over the shoulders, whereupon the draw string being suitably manipulated, adjustment of the garment and its support about the bust of the wearer may be secured in the usual way.

35 It will be noted that by my invention I effect a series of marked advantages, both in manufacture and use, among them the following: The elimination of the material formerly used to make the shoulder straps 40 and the substitution of a simple hem, or equivalent, for holding the draw string across the front and back of the neck opening of the body of the garment, effects a marked saving in manufacture, both as to material and labor. The garment is equally 45 well adapted without alteration or change of any kind to dual uses, to wit: it has shoulder straps for ordinary or day wear, and is without them for evening wear, the 50 garment being equally well supported and fitting equally well in both instances. Any given size of garment is adapted to a wider range of use for women of varying size than heretofore and there is perfect fit of the

shoulder strap without any objectionable 55 accumulations or bunching of material.

Referring to the drawings, Figure 1 is a front elevation of a lady's undervest embodying my invention, the upper part of the garment being distended to approximately 60 its full size; Fig. 2 is a view similar to Fig. 1, in which the draw string has been shortened and the material of the garment at the upper part and neck opening gathered together; Fig. 3 is a view of the draw 65 string, the upper part of the garment being dotted in.

In the drawings 1 represents the body of the garment which may be made of any preferred material and may be fashioned as 70 desired, either a tubular knit fabric or cut from flat piece goods, the latter being the construction shown in the drawings.

2, 2, represent the arm openings, 3 the 75 neck opening.

4 is a hem at the neck opening of the garment back and front, the ends 5 of which hem at the arm holes are left open.

6 is the draw string which is passed through the hem in the front and back of 80 the garment, projecting through the open ends 5 of the hems, forming loops or straps beyond the same. The free ends of the draw string pass through an opening 7, preferably made in the center of the front of the 85 garment, where they are tied in a suitable bow knot 8, as shown, or otherwise secured.

In view of what has been said, the operation is obvious. When it is desired to 90 use the garment for day wear, the arms of the wearer are thrust through the arm openings in the usual way, with the loops of the draw string over the shoulders and the draw string is then lengthened or shortened to suit the size or the desires of the wearer. 95 It may be that the garment will be most acceptable when the neck opening is distended as shown in Fig. 1, or if the woman be small, then the draw string may be shortened and the material of the garment 100 gathered together, in which event, of course, the bow 8 will be somewhat larger. When it is desired to use the garment for evening wear, then the loops which constitute the shoulder straps will be passed directly beneath the arms of the wearer and the draw string drawn sufficiently taut across the 105 upper part of the bust to afford the usually

desired snug fit and the requisite support for the garment, in which event the loops of the bow knot 8 and the free ends of the draw string will be somewhat larger.

It will be obvious to those who are familiar with such matters that although I have illustrated the invention as embodied in a lady's undervest, it is, as stated above, adapted to a variety of ladies' undergarments and further that the garment may be fashioned in any way desired, either of tubular knit fabric or cut from flat piece goods; also that instead of a hem formed of the material of the garment, any other desired means may be employed for holding the draw string in the stated relation to the upper part of the back and front thereof.

I claim:

A garment of the class stated adapted to dual uses, having a single, continuous draw string movably engaged with both the front and back of the neck opening and which alone passing over the shoulders constitutes the shoulder straps, the entire length of the draw string being of equal bulk and freely movable throughout relative to the garment, whereby the latter is comfortably adapted without removal of the draw string from the garment to both day and evening wear.

In witness whereof I have signed my name to this specification.

ERNST T. SEIFERT.
